UNITED STATES PATENT OFFICE.

JOHN S. DEVLIN, OF NEW YORK, N. Y.

BOILER ATTACHMENT.

1,100,545.

Specification of Letters Patent. Patented June 16, 1914.

Application filed June 24, 1913. Serial No. 775,475.

To all whom it may concern:

Be it known that I, JOHN S. DEVLIN, a citizen of the United States, and a resident of the city of New York, borough of Brooklyn, in the county of Kings and State of New York, have invented a new and Improved Boiler Attachment, of which the following is a full, clear, and exact description.

- 10 The object of the invention is to provide a new and improved attachment for water tube boilers and other boilers arranged for retarding the travel of the smoke and gases from the boiler into the draft flue, to insure 15 complete combustion of the burning fuel without interfering with the natural draft of the boiler. In order to accomplish the desired result use is made of a casing arranged within the combustion chamber of 20 the boiler at the entrance to the draft flue, a skeleton support held in the said casing and carrying a series of bell-shaped retarding members spaced apart, and a grid movable toward and from the said retarding 25 members and having openings in register with the said members.

A practical embodiment of the invention is represented in the accompanying drawings forming a part of this specification, in 30 which similar characters of reference indicate corresponding parts in all the views.

Figure 1 is a side elevation of the attachment as applied to a water tube boiler, partly shown in section; Fig. 2 is a face 35 view of the same with parts of the grid broken out; and Fig. 3 is an enlarged sectional side elevation of the attachment as applied.

The boiler A to which the attachment is 40 shown applied is a water tube boiler of the usual type and is provided with a combustion chamber A' and a draft flue B leading from the said combustion chamber A' to a chimney. In the draft flue B is arranged a 45 damper C for controlling the draft of the boiler, and the said damper is provided with a shaft C' journaled in the sides of the draft flue and provided on one outer end with an arm D connected by a chain E with a device for automatically controlling the damper C according to the steam generated by 50 the boiler. Thus when the boiler pressure falls below normal pressure then the damper is automatically opened to increase the 55 draft in the boiler, but when the boiler

pressure exceeds the normal pressure then the damper moves into closed position to cut off the draft correspondingly.

The boiler thus far described is of the usual construction and the attachment is applied to this boiler in the following manner: Within the combustion chamber A' and at the entrance to the draft flue B is arranged a casing F open at the end and provided with a horizontal bottom F', vertical sides F² and an upwardly and outwardly slanting roof F³, so that the smoke and gases in the combustion chamber A' readily pass into and through the casing F on their way to the draft flue B. The sides F² of the casing F are provided with lugs F⁴ secured by bolts F⁵ or other fastening means in the inner face of the end wall A² of the boiler A, as plainly indicated in the drawings.

Within the entrance end of the casing F 75 is arranged a skeleton support G, preferably formed of horizontal and vertical bars spaced suitable distances apart and supporting bell-shaped retarding members H set equal distances apart in vertical and horizontal rows, as plainly indicated in Fig. 2.

A grid I is arranged adjacent the entrance end of the casing F and is formed of horizontal and vertical bars similar to the bars of the support G and so spaced apart to 80 form openings for the reception of a corresponding bell-shaped retarding member H.

The openings are square and when the grid I is moved toward the entrance end of the casing F (see dotted lines in Fig. 3) then 90 the openings receive the bell-shaped members H, but as the openings are square and the members H are circular it is evident that sufficient space is formed at the corners of the openings for the passage of the smoke 95 and gases from the combustion chamber A' to the casing F and to the draft flue B.

When the grid I is moved away from the entrance end of the casing F, as shown in full lines in Figs. 1 and 3, then an unobstructed space is had between the adjacent bells for the passage of the smoke and gases to the casing F and the draft flue B. By reference to Fig. 2 it will be noticed that the retarding members H are mounted on the 100 horizontal and vertical bars of the skeleton support G at the junction of the side bars so that the corners of the openings in the grid I provide an unobstructed passage for the smoke and gases to the casing F at the 105 110

time the grid I is in closed position as above mentioned. One of the horizontal bars I' of the grid I is mounted to slide on guideways J attached to the sides F² of the casing F whereby the grid I is supported and free to slide to and from the entrance end of the casing F. The grid I is provided at its middle with a button K having its shank engaged by an eye in a depending arm L of 10 a rock shaft L' journaled in the outer ends of the guideways J. One outer end of the shaft L' is provided with an arm L² extending approximately horizontally and connected at its free end by a link N with 15 the damper arm D previously mentioned, so that when the damper C is actuated a rocking movement is given to the shaft L' which by the arm L moves the grid I toward or from the entrance end of the casing 20 F. When the damper C is in vertical closed position, as shown in Figs. 1 and 3, then the grid I is in completely open position relative to the retarding members H, and when the damper C is moved into open position then 25 the grid I is moved into correspondingly closed position relative to the retarding members H, as indicated in dotted lines in Fig. 3.

By the arrangement described the desired 30 draft is provided in the boiler but the smoke and gases are retarded in their outflow by the bell-shaped retarding members H and the grid I, so that the smoke and gases are retained within the combustion chamber A' 35 and are burned therein to insure complete combustion of the fuel. By making the retarding members H of bell shape the smoke and gases striking a member are readily diverted over the curved edges to pass into the 40 casing F and through the draft flue B.

The attachment shown and described can be readily applied to boilers as now constructed as the casing F can be readily attached to the wall A², and connection can be 45 made with the damper arm D to cause the grid I to move with the damper C only in a reverse direction.

Having thus described my invention, I claim as new and desire to secure by Letters 50 Patent:

1. In a boiler, the combination with the draft flue having an automatic damper, of a casing within the boiler at the entrance of the said draft flue, a series of smoke-retarding 55 members mounted at the entrance end of the said casing and spaced apart, a movable grid having openings in register with the said retarding members, and connecting means connecting the said damper with the 60 said grid to move the latter toward and from the entrance end of the said casing.

2. In a boiler, the combination with the draft flue having an automatic damper, of a casing within the boiler at the entrance end 65 of the said draft flue, a series of smoke-re-

tarding members mounted at the entrance end of the said casing and spaced apart, a movable grid having openings in register with the said retarding members, and connecting means connecting the said damper with the said grid to move the latter toward the entrance end of the said casing and the said retarding members on opening the damper. 70

3. In a boiler, the combination with the draft flue having an automatic damper, of a casing within the boiler at the entrance to the said draft flue, a skeleton support in the entrance of the said casing, a series of bell-shaped retarding members mounted on the said support and spaced apart, a grid having polygonal openings for the reception of the said retarding members, and means connecting the said grid with the said damper to move the grid into closing position on opening the damper and vice versa. 75

4. A boiler attachment, comprising a casing arranged within the boiler at the entrance to the draft flue, a skeleton support in the entrance of the said casing, a series of bell-shaped retarding members attached to the said support and spaced apart, a movable grid having polygonal openings for the reception of the said retarding members, and means for moving the said grid toward or from the entrance of the said casing. 80

5. In a boiler, the combination with the draft flue having an automatic damper, of a casing within the boiler at the entrance to the said draft flue, the casing being open at the front and rear, and having a horizontal bottom, vertical sides and a sloping roof, a skeleton support in the entrance of the said casing, a series of bell-shaped retarding members mounted on the said support and spaced apart, a grid having polygonal openings for the reception of the said retarding members, and means connecting the said grid with the said damper to move the grid into closing position on opening the damper and vice versa. 100

6. A boiler attachment, comprising a casing arranged within the boiler at the entrance to the draft flue, a skeleton support in the entrance of the said casing, a series of bell-shaped retarding members attached to the said support and spaced apart, a movable grid having polygonal openings for the reception of the said retarding members, guideways on the said casing and slidably supporting the said grid, and means for moving the said grid toward or from the entrance of the said casing. 110

7. A boiler attachment, comprising a casing arranged within the boiler at the entrance to the draft flue, a skeleton support in the entrance of the said casing, a series of bell-shaped retarding members attached to 120

the said support and spaced apart, a movable grid having polygonal openings for the reception of the said retarding members, guideways on the said casing and slidably supporting the said grid, a crank shaft journaled on the said guideways and provided with an angular arm connected with the said grid, an automatic damper in the draft flue, and a connection between the damper and the crank shaft to rock the latter on **10** opening and closing the damper.

In testimony whereof I have signed my name to this specification in the presence of two subscribing witnesses.

JOHN S. DEVLIN.
